UNITED STATES PATENT OFFICE.

DOMINICK KULAGE, OF ST. LOUIS, MISSOURI.

PORTABLE GROOVE CUTTER.

Application filed January 27, 1926. Serial No. 84,043.

This invention relates to an improved machine for use in grooving the underside of the bottom rail of a window sash.

The general object of the invention is to provide a portable device having means, such as a circular saw, for cutting a groove, and which is adapted to permit a window sash to be moved over the same with the underside of its bottom in engagement with the grooving member, so that a groove will be cut in the bottom of the sash.

The device is particularly intended for use in connection with applying weatherstrips to a window frame, and enables the operator to rapidly groove the underside of the bottom rail of the window sash, so that it will receive the weatherstrip which is placed in position on the bottom of the window frame.

The invention embodies a case or box, ordinarily oblong in shape, and having mounted therein a motor provided with a circular saw on one end of its shaft, means for connecting the motor to an ordinary electric light socket, and a lid provided with a slot through which the upper part of the saw projects, and with an adjustable guiding part which enables the position of the window sash, when placed on the lid, to be correctly adjusted relative to the saw, so that the groove may be formed at the desired point in the bottom of the sash.

The invention is illustrated in the accompanying drawing, in which—

Figure 1 is a plan view of my improved portable groove-cutter;

Figure 2 is a view in front elevation of the same;

Figure 3 is a plan view with the lid on the device raised;

Figure 4 is an end view of the device;

Figure 5 is an enlarged sectional view on the line 5—5 of Figure 1; and

Figure 6 is a sectional view on the line 6—6 of Figure 1.

Referring now to the drawing, the numeral 1 indicates the casing of my device, which is rectangular in shape and, roughly, has the appearance of an ordinary tool chest, although somewhat larger. The casing is provided with a lid 2 hinged thereon at the rear, as indicated at 3, which lid is provided on its upper side along the front edge with a metal strip 4, forming a base for supporting the sash when it is being grooved. At points equally removed from opposite ends of the lid, 53 said lid and the strip 4 are cut through to

provide slots 5 extending parallel with the ends of the lid. Mounted on top of the strip 4 at the rear side thereof is a metal guide bar 6, which has counter-sunk screws 7 extending through the same from the top and through the slots 5 (see Figure 5), each of which screws is provided at its lower end with a washer 8 and a nut 9. By loosening the nuts 9, the guide bar 6 can be adjusted in position on the strip 4 and then secured in such adjusted position by tightening said nuts. Centrally of the strip 4 and near the rear edge thereof, said strip and the lid 2 are cut through to provide a slot 10, extending longitudinally of the lid (Figures 1 and 6), 70 through which projects the upper side of a circular saw 11, which is mounted on the outer end of the shaft 12 of an electric motor 13. This motor is secured to the floor of the casing 1, as by means of bolts 14. Mounted 75 on a cross-piece 16 near one end of the box is a switch 17, which is connected to the motor by means of conductors 18. Leading from the switch 17 is a flexible conductor 19 provided at its outer end with an ordinary plug 20 for connection with an electric light socket. The end of the casing at which the switch is located is centrally apertured, as indicated at 21 (Figure 4), to permit a turn-button 22 on the switch 17 to project through 80 said aperture. The material of the end of the casing is preferably reamed out around the opening 21, as indicated at 23 in Figures 3 and 4, to provide a space for the operation of the turn-button, thus obviating having the latter project beyond the surface of the end of the casing. The cross-piece 16 and the adjacent end of the casing 1 are grooved, as indicated at 24, (Figure 4) to receive the conductor 19, so that the lid 2 may be firmly 85 closed. Corresponding grooves 25 are formed in said cross-piece and the end of the casing near the front end of the latter, which permit the conductor 19 to be bent upon itself and coiled up in the casing 1 with part of the conductor resting in these grooves 24. This arrangement permits the lid to be closed and locked and secured in the closed position, as by keepers 26, when the device is not in use 100 or is being carried about. In this position of the parts, a portion of the conductor 19 will project from the end of the casing, as shown in Figures 1, 2, and 4.

The above described means of arranging for 110

the disposition of the conductor 19 is preferred because of the fact that the conductor is given a very tight fit in the grooves 24 and is not ordinarily removed therefrom. By 5 this means, I prevent movement of the conductor at the point of its connection with the switch 17, and also obviate wear of the insulation which would result from constantly placing the conductor into and removing it 10 from the grooves 24. The additional grooves 25 are, therefore, necessary to permit the portion of the conductor projecting beyond the casing to be inserted in the box and the lid to be firmly closed. Other ways of arranging 15 the conductor could, of course, be employed. The front of the case is provided with a handle 27, by means of which it may be carried about, and its upper side is recessed and provided with a hood 28 covering the recess to 20 form a housing for the upper part of the motor.

In operation, the window sash is removed from the frame and placed with its bottom resting on the strip 4 and one of its sides flush 25 with the side of the bar or guide 6. The plug 20 having been inserted in an electric light socket and the saw 11 being in operation, the sash is moved along the guide bar 6 into engagement with the saw 11, which operates to 30 cut a groove centrally of the bottom of the sash and longitudinally thereof.

The device is, of course, carried by the operator to the various places where he is applying weatherstrips to the windows, and affords a very rapid means of grooving the bottom rail of a window sash as compared with the hand implements commonly employed for that purpose. In addition, it affords a more cleanly method of procedure, in that all of the saw-dust is caught by the box or casing 1 and is thus prevented from being scattered over the floor of the room where the sash is being grooved.

I claim:

45 1. In a device of the class described embodying a casing having a hinged lid and a motor-driven saw mounted therein, a flexible conductor operatively connected with said motor and projecting beyond the casing, the upper edge of said casing being grooved to 50 permit the conductor to be embedded therein and having an additional groove to permit the

conductor to be turned back upon itself and inserted therein and the remaining portion of the conductor coiled within the casing and the 55 lid to be closed to lie flush with the upper edge of the casing, thereby preventing the necessity of removing the conductor from the first-mentioned groove.

2. A portable groove-cutter for use in 60 grooving the underside of a window sash, comprising a casing provided on one side with a flat portion having a slot, a motor secured on a wall of said casing, a circular saw mounted directly on the shaft of said motor and projecting at one side through said slot, the construction permitting the casing to receive the saw-dust produced by the operation of the saw, and a guide-bar adjustably mounted on said flat portion for guiding the 65 movement of the sash along said flat portion and over the saw.

3. A portable groove-cutter for use in 70 grooving the underside of a window sash, comprising a casing having a lid provided 75 with a flat portion having a slot, a motor secured on the bottom of said casing, a circular saw mounted directly on the shaft of said motor and projecting at one side through the slot in said lid, the construction permitting 80 the casing to receive the saw-dust produced by the operation of the saw, and a guide-bar adjustably mounted on the flat portion of said lid for guiding the movement of the sash along said flat portion and over the saw. 85

4. A portable groove-cutter comprising a casing provided on one side with a flat portion having a slot, a motor secured on a wall of said casing, a circular saw mounted directly on the shaft of said motor and projecting at 90 one side through said slot, the construction permitting the casing to receive the sawdust produced by the operation of the saw, means for guiding the movement of a sash along said flat portion and over the saw, a switch mounted in one end of said casing having a turn-button located on the outer side of said end, conductors extending from said switch to the motor, and a flexible conductor extending from said switch to the outside of the casing. 95

In testimony whereof, I have hereunto set my hand.

DOMINICK KULAGE.
